UNITED STATES PATENT OFFICE

JAMES HENRY BOWMAN, OF BRIDGEPORT, OHIO, ASSIGNOR TO WHEELING STEEL CORPORATION, OF WHEELING, WEST VIRGINIA, A CORPORATION OF DELAWARE

CORNER MITER FOR SCREEDS

Application filed July 26, 1929. Serial No. 381,323.

This invention relates broadly to corner miters, and more particularly to a miter for use with a screed of the character employed in the plastering of walls or the like.

5 The primary object of the invention is to provide a device of the character mentioned which may be readily and quickly attached to a screed when it is desired to form a corner in the plastering of a wall.

10 A further object of the invention is to provide a device of the character mentioned which forms a true continuation of the screed when applied thereto.

15 Another object of the invention is to provide a sheet metal miter which is formed of a single sheet of material arranged to frictionally engage and connect several screeds and to be held against accidental displacement.

20 A still further object of the invention is to provide a device of the above character which is efficient in operation and which may be economically manufactured.

25 These and other objects will be apparent throughout the course of the following description and accompanying drawings, in which—

30 Fig. 1 is a top plan view of a screed with my improved miter applied to each of its ends;

Fig. 2 is a front elevation of same;

Fig. 3 is a sectional view taken on line 3—3, Fig. 2;

35 Fig. 4 is a sectional view taken on line 4—4, Fig. 2; and—

Fig. 5 is a perspective view of an outside miter.

40 Referring in detail to the drawings, A designates generally the usual screed formed of a single sheet of material bent longitudinally to form a rib 1 of substantially V-shape in cross section having outwardly extending webs 2 provided with openings 3 through 45 which nails or the like are driven to attach

the same to the laths of a room to be plastered.

The reference character B indicates a miter for an outside corner and C a miter for an inside corner, which corners may occur about door and window frames and in instances where ceiling supporting piers project into a room.

The outside corner miter B comprises a body portion 4 of sheet metal formed with a pair of outwardly extending arms or fingers 5 offset as at 6 and disposed at right angles to the body portion and to each other. Formed integral with the body portion intermediate the offset portions 6 and rising vertically therefrom is a right angled member 7 having its lower edge spaced from the inner edges of the arms 5, as shown in Figs. 3 and 5.

The inside corner miter C comprises a body portion 10 of sheet metal formed with a pair of outwardly extending arms or fingers 11 offset as at 12 and disposed at right angles to the body portion and to each other. Formed integral with the body portion intermediate the offset portions 12 and rising vertically therefrom is a right angled member 13 having its lower edges spaced from the upper or outer edges of the arms 11.

45 In applying the miter B to the screed when it is desired to form a corner which projects into a room, one of the outwardly projecting portions 5 is inserted between the sides of the rib 1 and with the adjacent portion of the right angled member 7 overlying one of the webs 2, the space between the portions 5 and 7 being such that the miter is frictionally retained in position upon the screed. The offsetting of the portions 5 relative to the body 4 is such so that the upper face of the body 4 and its front edge are disposed in substantially the same plane as the upper face and front edge of the rib 1 of the screed. This arrangement permits the ready smoothing and truing of the plaster by a plasterer's level 50

placed upon the front edges of the ribs of adjacent screeds, the ribs forming guides for the level and a depth gauge for the plaster.

The application and operation of the inside corner miter C is substantially the same as that employed in the use of the miter B.

The disclosure in Fig. 1 of the drawings is merely by way of illustration, and it is to be understood that either of the miters B and C may be placed upon either of the ends of the same screed.

What is claimed is—

1. A corner miter for use with a screed having a centrally disposed rib comprising a body member formed of sheet metal, offset portions extending outwardly therefrom and at right angles to the body member and to each other, and a vertically disposed angular member secured to the body member and having its lower edges spaced from the inner edges of the offset portions, the offset portions being adapted to engage between the sides of said rib and the angular member having a part overlying the outer face of the screed.

2. A corner miter for use with a screed having a rib, comprising a body member formed of sheet material, a pair of arms extending outwardly from the body member at right angles to the latter and to each other, and an angular member secured to said body and disposed at right angles to said arms and spaced therefrom, the arms being adapted to engage between the sides of said rib and the angular member having a portion overlying the outer face of the screed.

3. A corner miter for use with a screed, comprising a body member, a pair of arms carried by said body and disposed substantially at right angles to each other, and a member carried by said body and disposed substantially at right angles to said body member and arms, said arms being adapted to be inserted between adjacent portions of the screed and said angularly disposed member overlying the outer face of the screed.

4. A corner miter for use with a screed having a rib, comprising a body, a pair of arms carried by and offset from said body, said arms being disposed substantially at right angles to each other and having their upper faces disposed in a horizontal plane, and an angular member carried by said body and disposed at right angles to said arms, said member being disposed adjacent to said arms, said arms being adapted to engage between the sides of said rib, and the free portions of the angular member being formed to engage the outer face of the screed.

5. A corner miter formed of a single sheet of material, comprising a body portion, a pair of arms formed integral with and offset from said body portion, and a vertically disposed angular portion formed on said body intermediate the offset portions of the arms and arranged substantially at right angles

to said arms, the lower edges of the angular portion being spaced from the inner edges of the arms.

6. A corner miter for use with screeds having a hollow rib and an attaching member, comprising a body and a vertically extending portion formed on said body, the body having a part formed to engage within the rib and the vertically extending portion being formed to engage the outer face of the attaching member of the screed.

In testimony whereof, I affix my signature.

J. HENRY BOWMAN.
